UNITED STATES PATENT OFFICE

127,105

DESIGN FOR A BROOCH OR SIMILAR ARTICLE

Irving Borek and Maurice H. Meyer,
New York, N. Y.

Application March 24, 1941, Serial No. 99,789

Term of patent 3½ years

To whom it may concern:

Be it known that we, Irving Borek and Maurice H. Meyer, both citizens of the United States, residing at New York, in the county of Bronx and State of New York, and Manhattan, in the county of New York and State of New York, respectively, have invented a new, original, and ornamental Design for a Brooch or Similar Article, of which the following is a specification, reference being had to the accompanying drawing, forming part thereof, wherein—

Fig. 1 is a top plan view of a brooch or similar article showing our new design.

Fig. 2 is a front view thereof.

While we have shown our new design embodied in a brooch or similar article, it is contemplated that the same may be embodied in similar articles of jewelry without departing from the spirit of our invention.

We claim:

The ornamental design for a brooch or similar article, substantially as shown and described.

IRVING BOREK.
MAURICE H. MEYER.
